UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

TRUCK.

SPECIFICATION forming part of Letters Patent No. 408,027, dated July 30, 1889.

Application filed March 14, 1889. Serial No. 303,270. (No model.)

To all whom it may concern:

Be it known that I, EDWARD WILLIAM MACKENZIE HUGHES, of Chicago, Cook county, Illinois, have invented a new and useful Improvement 5 in Trucks, of which the following is a full, true, and exact description, reference being had to the accompanying drawings.

This invention relates to an improved construction of metallic trucks and truck-frames 10 for railroad-cars, especially as adapted to six-wheeled cars. The parts herein referred to are generally made of pressed steel.

My invention will be readily understood from the accompanying drawings, in which—

15 Figure 1 represents a plan view; Fig. 2, an outside lateral elevation of the side of the truck-frame; Fig. 3, a section through Fig. 1 on the line *v v*; Fig. 4, a section through Fig. 1 on the line *x x*; and Fig. 5, a section through 20 Fig. 1 on the line *y y*, or the line *z z*, Fig. 3.

My truck consists, generally, of the side frames A A, which are formed of double angle-iron of the shape shown, having flanges B and C, as clearly shown in Fig. 4. The end 25 pieces D D are hollow boxes fitting over the ends of the side pieces A A. The truck-frame has an additional framing of transverse pieces F F, which have the general form of channel-beams, Fig. 3, and longitudinal pieces E E, 30 preferably box-shaped, as shown in Fig. 3.

The channel-beams F F, which may be box-shaped, if desired, rest upon the inside flanges C C, while the pieces E E rest, and are supported within the corresponding boxes F and 35 D. The frames for the axle-boxes are strengthened within by having the parts K K folded back, as shown. The two inside brackets P P rest upon the inwardly-projecting flange C, while the two outer ones P' P' rest upon the 40 upper surface of the cross-beams F. These brackets are for the purpose of carrying the swinging links for the bolster-planks. The

center plate J rests upon the arch-beams H H. The ends of these arch-beams are fastened to the transverse beams G G, and the 45 arch-beams are attached thereto by the upper plates L L and the lower plates M M, as shown. The attachment between the center plate J and its attached portions and the truck-frame may be done in any suitable manner, and is not indicated in these drawings. The various parts 50 are fastened together in any well-known way, as, for instance, by bolting or welding.

What I claim as my invention, and desire to secure by Letters Patent, is—

1. The combination of the side pieces A A, 55 having flanges B and C on alternate sides thereof, with the end boxes D D, substantially as and for the purposes described.

2. The combination of the side pieces A A, 60 having internal flanges C, with the end box D, and the transverse framing F, supported upon the flanges C, substantially as described.

3. The combination of the side pieces A A, 65 having internal flanges C, with the end box D, the transverse framing F, supported upon the flanges C, and the longitudinal beams E E, resting on the flanges of the parts F and D, substantially as described.

4. The side frames having flanges B C, the 70 internal flange C being folded back, as at K, substantially as described.

5. The arch-beam connections shown, consisting of the two channel arch-beams H H, and the cross-pieces G G, attached to the 75 beams H H by plates L M, substantially as described.

In testimony whereof I have signed my name to this specification in the presence of two subscribing witnesses.

EDWARD WILLIAM MACKENZIE HUGHES.
